UNITED STATES PATENT OFFICE

ALFRED R. WILSON, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF DELAWARE

HOIST ANCHORAGE FOR CAR ROOFS

Application filed March 1, 1926. Serial No. 91,598.

The invention relates to car roofs designed for use on cars intended for the carrying of heavy cargoes such, for instance, as automobiles and other heavy machines.

5 It is the object of the invention to provide an anchorage for hoisting apparatus by means of which such heavy units may be lifted and properly positioned within the car.

10 It is a further object to accomplish this result without cutting down on the clearance space or interfering with the carrying of a full load.

15 With these objects in view, the invention consists in the construction as hereinafter set forth.

In the drawings:

Figure 1 is a cross section through the roof portion of a railway car to which my improvement is applied.

20 Figure 2 is an enlarged cross section showing the hoist anchorage.

Figure 3 is a longitudinal section thereof.

25 Figure 4 is a plan view showing a number of the carlines and the manner of attaching the hoist anchorage thereto.

Figure 5 is a longitudinal section thereof.

The car roof to which my improvement is applied may be of any suitable construction having sufficient strength but preferably is 30 one in which the carlines A have portions A' thereof parallel with the sloping roof and a central portion A² which passes horizontally beneath the ridge pole B. C are the side plates on which the carlines are supported.

35 My improved hoist anchorage is preferably formed of a structural beam D which extends longitudinally of the car either the entire length thereof or for whatever distance 40 may be required. This beam is located in the centre of the car beneath the ridge pole and also below the horizontal portions A² of the carlines A. Where, as shown, both the carlines and the beam are formed of channel members having laterally extending side flanges, the flanges E of the beam D may be secured by riveting to the flanges F of the carlines at each point of overlap. It is not, however, essential that either the beam or the 45 carlines should be of this particular cross sec-

tion as it is obvious that any suitable structural shape may be substituted therefor.

With the construction as described, it will be noted that the bottom of the beam D is still somewhat above the plane of the top of the side plates so that it does not in any way interfere with the rectangular cross sectional space within the car. It will also be observed that the depth of the carlines provides a clearance space between the beam and the ridge pole B through which a rope, chain or other anchorage or hoisting means may be passed. The load applied at any one point in the beam will be distributed not only to the immediately adjacent carlines but to the 65 whole series so that there will be no danger of overloading or injuring the roof.

What I claim as my invention is:

1. The combination with a sloping car roof including a ridge pole and series of carlines, of a beam extending longitudinally beneath said carlines in spaced relation to said roof and rigidly attached to said carlines to constitute a hoist anchorage, the said beam being located above the plane of the edge portions of said roof.

2. The combination with a car roof having a ridge pole and a series of carlines extending transversely thereof, of a beam extending longitudinally and centrally beneath said carlines in spaced relation to said roof and rigidly attached to said carlines, said beam constituting a hoist anchorage located above the plane of the ends of said carlines.

3. The combination with a car roof having a ridge pole and a series of carlines having central portions passing beneath said ridge pole, of a beam extending longitudinally beneath said ridge pole and carlines and rigidly attached to the latter, said beam constituting a hoist anchorage located above the end portions of said carlines.

4. The combination with a car roof having a ridge pole and a series of carlines having portions conforming to the slope of the roof and central horizontal portions passing beneath said ridge pole, side plates on which said carlines rest, and a beam extending longitudinally beneath said ridge pole and carlines being rigidly attached to each carline.

and constituting a hoist anchorage located above the plane of the top of the side plates of the car.

5. The combination with a car roof having 5 a ridge pole and a series of carlines passing therebeneath, said carlines being of an inverted channel section having outwardly extending side flanges, of a beam formed of an upwardly opening channel having laterally extending side flanges, said beam extending longitudinally of the car and being arranged centrally beneath the ridge pole and carlines, the flanges thereof being rigidly secured to the flanges of the carlines.

10 15 6. In a car roof, in combination a ridge pole, a plurality of U-shaped carlines having their base portions secured to the said ridge pole and a beam constituting a hoist anchorage secured to the leg portions of the said 20 U-shaped carlines centrally below the said ridge pole.

7. A railway car comprising side plates, carlines secured to the side plates and having oppositely disposed laterally extending 25 flanges, roof sheets secured to the carlines, and means carried by the laterally extending flanges of the carlines constituting a hoist anchorage, said means being disposed in spaced relation to the underside of the roof 30 sheets.

8. The combination with a car roof, of a ridge pole and a series of carlines passing therebeneath, of a beam formed of an upwardly opening channel having laterally extending side flanges, said beam extending longitudinally of the car and being arranged centrally beneath the ridge pole and carlines, the flanges of the beam being attached to the carlines.

40 45 9. The combination with a car roof including a series of carlines, of a metallic structural beam of channel cross section with laterally extending side flanges, said beam extending longitudinally beneath said carlines and directly rigidly attached thereto to constitute a hoist anchorage.

10. The combination with a car roof having a series of inverted channel carlines, of a beam of channel cross section with laterally extending side flanges, said beam extending longitudinally and centrally of the car with its side flanges secured to said carlines and constituting a hoist anchorage.

55 60 11. The combination with a car roof having a series of carlines of inverted channel cross section with outwardly extending side flanges, of a beam formed of channel cross section with laterally extending side flanges, said beam extending longitudinally and centrally of the car with its side flanges secured to the side flanges of said carlines and constituting a hoist anchorage.

65 12. The combination with a car roof, of a beam of upwardly opening channel cross section with laterally extending side flanges, said

beam extending longitudinally beneath said car roof and being secured thereto.

13. In a car roof, the combination with a series of carlines, of a hoist anchorage beam 70 extending transversely thereof and longitudinally of the car, one of said elements being of channel cross section with laterally extending side flanges and both of said side flanges being secured to the transversely extending element.

14. In a car roof, the combination with a series of carlines, of a hoist anchorage beam 75 of channel cross section with laterally extending side flanges, said beam extending longitudinally of the car and transversely of the 80 said carlines, and both of said side flanges being secured to a carline.

15. In a car roof, the combination with a series of carlines of inverted channel cross section 85 having laterally extending side flanges, of a hoist anchorage beam of channel cross section with laterally extending side flanges, said beam extending longitudinally of the car transversely of said carlines and both of the side flanges of the beam being 90 secured to both of the side flanges of a carline.

In testimony whereof I affix my signature.
ALFRED R. WILSON.
